REDUCTION MILL

George Foye Ainsa, San Francisco, Calif., assignor of five-eighths to Dolores C. Ainsa, Berkeley, Calif.

Application April 1, 1935, Serial No. 14,812

7 Claims.

(Cl. 83—46)

The present invention relates generally to a reducing mill of the type in which an agglomerate of loose and lumpy material is reduced or pulverized by a rubbing action between the particles thereof, and more particularly to an improved form of mill wherein the particles of the agglomerate are projected by centrifugal force against a stationary or rotating impact receiving member to thus effect a reduction of the agglomerate by impact operation.

An object of the present invention is to provide a reduction mill for reducing and pulverizing an agglomerate which operates on the impact principle to reduce the agglomerate to powdered form.

Another object of the present invention is to provide a reduction mill wherein the larger particles of the agglomerate will be reduced and disintegrated in a continuous manner by interimpaction created by centrifugal force.

Another object of the present invention is to provide in a reducing mill of the above character means for returning the unreduced particles of the agglomerate to the reducing elements of the mill and separating the finer particles therefrom by a process of flotation.

Another object of the present invention is to provide a reducing mill which is an improvement upon the mill illustrated and described in my co-pending application for patent, Serial Number 692,073, filed October 4, 1933, and entitled Attrition mill.

In the art to which the present invention relates there has been devised a large number of mills for reducing ores and other agglomerate by retaining portions thereof in a receptacle by centrifugal force and causing a mass of agglomerate thus held to rub against a second stationary or relatively movable mass of the agglomerate.

In reducing mills of this character the agglomerate is reduced solely by a rubbing action which takes place between the relatively movable particles of the agglomerate as it travels under the influence of centrifugal force and passes out of the mill between grinding rings disposed about the periphery of the centrifugally operating rotor elements. Such a reducing action requires the exertion of a high pressure between the particles and consequently a considerable amount of power is necessary for satisfactory results. Therefore, it is a further object of the present invention to provide an improved reduction mill in which the particles will be thrown by centrifugal force against an impact member and against each other and thus reduced by impact action with-

out subjecting the mass to an excessive grinding pressure.

In accordance with the present invention the agglomerate is fed by gravity into a horizontally disposed rotating element and is thrown therefrom by centrifugal force against an impact receiving element to reduce same. The heavier unreduced particles are then redirected by suitable means back into the centrifugal rotating element until the agglomerate is reduced to the desired degree of fineness, after which the finely divided agglomerate is conducted away from the mill by flotation or other means.

For a better understanding of the invention and the mode of operation reference should be had to the accompanying drawing wherein there is shown, by way of illustration and not of limitation, a preferred embodiment thereof.

In the drawing wherein like numerals designate like parts throughout the several views;

Figure 1 is a side elevation, partially in section, showing a reducing mill constructed in accordance with this invention.

Figure 2 is an end elevation, with parts broken away and in section, taken along line II—II of Figure 1, and

Figure 3 is a fragmentary sectional view showing modified details of construction suitable for a mill of the type contemplated by this invention.

In Figure 1 of the drawing there is illustrated in its entirety a mill, constructed in accordance with this invention, which is particularly adapted to the reduction of loose and lumpy material, such as ores, cement, rock, clay and the like. As here shown, the various elements of the mill are mounted in associated relation upon a suitable structural iron frame 10 having a pedestal 11 at one end upon which there is journalled a centrifugally operating agglomerate throwing bowl-like rotor element 12, and at the other end of the frame 10 there is a suitable platform arrangement 13 to facilitate the feeding of the material to be reduced to the mill, as will hereinafter appear. The centrifugal agglomerate throwing rotor 12 is carried by a horizontally disposed shaft 14 which is journalled in bearings 15 and driven through a belt 16 by an electric motor 17. Between the pedestal 11 and the platform 13 the frame 10 is adapted to support a rotatable drum-like housing which is here designated generally by the numeral 18. This housing 18 is provided at its ends with rails 19 and 20 that engage and ride upon spaced supporting rollers 21 and 22 in a manner well understood in the art. Between the rails 19 and 20 the rotatable housing 18 is

equipped with an annular driving rack 23 which in cooperation with a spur gear 24 upon the end of the shaft of a motor 25 is adapted to provide a driving means therefor.

5 The rotatable housing 18 has a portion 26 of reduced diameter which extends over the centrifugal rotor element 12 and this reduced portion carries an impact receiving lining 27 which in this figure of the drawing is shown as consisting of a plurality of comparatively heavy annular wear-resistant rings 28. The rings 28 fit snugly within the reduced portion 26 and are removable secured therein by means of tie-rods 29 so that they may be conveniently removed and interchanged with respect to each other so as to provide for a uniform wear of the impact surface provided thereby. In other words, in the arrangement illustrated, the rings 28 which are directly in line with the agglomerate thrown 10 from the centrifugal rotor 11 will be subjected to the most wear, while the rings 28 removed from this area will receive little or no wear, and therefore with this arrangement it is possible to avoid a renewing of the entire impact receiving lining 15 27 within the portion 26, by merely rearranging the rings 28 and thus renew only the particular area which has received excessive wear. In accordance with another aspect of this feature of my invention, it is possible to provide rings having 20 good wear-resistant characteristics at the wear receiving region and use other and cheaper rings at the other points where the wear is not great.

At the outer end of the housing 18 the portion 35 26 carries a partially closing flange arrangement 30 that serves to prevent the escape of the agglomerate thrown by the centrifugal rotor element 12. The other end of the portion 26 is open and in communication with a relatively larger portion 31 of the rotatable housing 18 so that, as the agglomerate is thrown against the impact receiving surface 27, both the reduced and unreduced particles of the agglomerate will be discharged into this larger portion 31 of the housing 18. Arranged about the interior of the 40 larger portion 31 of the housing 18 there is a plurality of agglomerate lifting buckets 32 which serve, as the housing 18 is rotated, to return the unreduced particles of agglomerate to a suitable hopper 33 that is disposed within the housing 18 so as to discharge said agglomerate into the centrifugal rotor element 12. The hopper 33 is 45 preferably mounted upon a projecting portion 34 of the platform structure 13 and it extends through a disk-like baffle 35 which is arranged 50 centrally and in spaced relation opposite the open end of the reduced portion 26 of the drum 18.

The upper half of the disk-like baffle 35 is rigidly secured upon the projecting portion 34 and the 60 hopper 33 is secured thereto by means of a bracket 36. The lower half of the disk-like baffle 35 is supported so that it may swing freely about a hinged support 37 to permit the discharge of the larger unreduced particles of agglomerate and prevent an excess accumulation of 65 agglomerate within the chamber formed by the wear-resistant rings 28. In order to reduce wear this disk-like baffle 35 is provided with a layer of vulcanized rubber 38 which extends outwardly 70 therearound a sufficient distance to prevent a direct throwing of the agglomerate from the centrifugal rotor element 12 into the larger portion 31 of the rotatable housing 18. With this arrangement the thrown agglomerate will be 75 confined within the chamber formed by the wear-

resistant rings 28 so that its only discharge from this chamber will be by gravity at the lower inner edge of the extending portion 26. In the event of an accumulation of an excess of agglomerate, or the presence of a large piece of agglomerate upon the wear-resistant rings 28, the lower half of the baffle-like member 35 will swing outwardly upon its hinged support 37 and thus permit the accumulated agglomerate to discharge itself by gravity into the larger portion 31 of the housing 10 15 18 as the latter rotates.

Extending into the outer end of the housing 18 there is a second hopper 39 which is adapted to discharge agglomerate into the portion thereof which contains the buckets 32. The hopper 39 15 is adapted to be supplied with agglomerate by any suitable means, for instance, by an operator upon the platform 13 and the buckets 32 are so arranged and inclined within the portion 31 of the housing 18 that they will elevate the 20 agglomerate introduced through this hopper and discharge it into the inner hopper 33 from which it will be directed into the centrifugal bowl-like rotor element 12. During this operation the buckets 32 will also operate to return the unreduced agglomerate discharged from the impact receiving surface 27, as previously described, to the hopper 33, where it will be subjected to a further action with the newly introduced agglomerate. For the purpose of separating the reduced agglomerate from the unreduced agglomerate the enlarged portion 31 of the housing 18 is provided with a transversely extending baffle 40. This baffle 40 is supported within the housing 18 with its outer edge in spaced relation with the 3: cylindrical wall of the housing 18 and upon the outer edge of this baffle 40 there is a truncated conical baffle-like member 41 which serves to prevent the escape of unreduced agglomerate through the spacing thus provided between the 4: baffle 40 and the outer wall of the housing 18. In one arrangement, the outer edge of the baffle 40 is welded to the buckets 32 so that an extending portion 42 upon each bucket will project through the spacing provided between the 4: baffle 40 and the outer wall of the enlarged portion 31 of the housing 18. With this arrangement it will be seen that as the agglomerate is elevated by rotation of the housing 18 the conical baffle 41 upon the baffle 40 will cause the agglomerate to fall by gravity back through the spacing above referred to and into the bucket containing portion of the housing 18. In the drawing the separating baffle 40 is shown as provided with an inwardly projecting annular extension 43 having a central opening sufficiently large to accommodate the discharge end of the hopper 39.

In this mill, as in the mill illustrated and described in my above identified copending application for patent, I provide for the discharge of the reduced agglomerate from the mill by means of a circulation of water. In this manner the finer particles of agglomerate will be decanted and/or separated and discharged from the mill by flotation. For the purpose of providing for such a circulation of water I have shown a water supply pipe 44 having a discharge nozzle 45 which is located within the housing 18 immediately over the buckets 32, and for the purpose of carrying the discharged and finely reduced agglomerate from the mill proper, I have shown a suitable inclined chute 46 through which the discharged water and reduced agglomerate will flow by gravity to any point for future treatment.

In a mill of the type contemplated by this invention the action which takes place, insofar as the impact feature of reduction is concerned, is somewhat similar to that which takes place in the well-known "Hadsel mill". However, in the mill of the present disclosure the agglomerate is thrown, at a high velocity, by centrifugal force against an impact receiving surface and as a result the impact is more intense than is the case in the "Hadsel mill", wherein the agglomerate is merely dropped by gravity upon an anvil.

The operation of the mill described above is as follows:

When the agglomerate to be reduced is placed in and discharged from the hopper 39 it will be raised by the buckets 32 as the housing 18 rotates and deposited into the hopper 33. The agglomerate thus deposited in the hopper 33 will then be directed into the bowl-like rotor element 12 and from there thrown by centrifugal force against the impact receiving lining 27 of the housing 18 where it will be broken up and thus reduced. The reduced agglomerate and such agglomerate as has not been reduced to the required fineness will fall by gravity from the impact receiving lining 27 into the larger portion 31 of the housing 18, where the finer particles of the agglomerate will be taken up by the circulation of water and carried out through the spacing about the baffle 40 and around the truncated conical portion 41, where it will be free to flow out of the mill into the chute 46, while the heavier unreduced portion of the agglomerate will remain behind. At this point it should be pointed out that the above action will only take place at the lower part of the housing 18, and since the circulation of water is unable to carry out the larger particles of the agglomerate at this point, it will be readily seen that such larger particles of agglomerate as find their way into the space provided around the baffle 40 will be directed back into the buckets 32 by the conical baffle 41 as it rotates upwardly out of the water. In order to facilitate this action, I also propose to incline the extending portions 42 of the buckets 32 so that such agglomerate as remains inside of the conical baffle member 41 will be directed back into the buckets 32.

In the drawing, the housing 18 is shown as provided with an end closure 47 upon which there is mounted a conically flared member 48 which provides a lip-like discharge outlet for the mill. In order to provide for a variation in the level of the water normally retained within the mill for separating purposes, member 18 carries a suitable ring 49 which may have an inside diameter corresponding to any desired level of water to be retained in the mill. In this connection it may be stated that by varying the level of the water within the mill it will be possible to control within certain limits the fineness of the agglomerate which will be discharged therefrom by the circulating water.

From the above it will be seen that the larger particles of the agglomerate will be acted upon in a continuous manner until they have been reduced to the required degree of fineness. It will be also apparent that, since the velocity of a centrifugally projected body is proportioned to its mass, the intensity of the impact feature of the mill may be varied by increasing or decreasing the speed of the centrifugal rotor 12. The coarseness of the finished material decanted from the housing 18 may be also controlled by

varying the depth and/or the rate of flow of the water therethrough.

In this mill the impact rings 28 are shown as carried by the housing 18 and as rotatable therewith. While this is a preferred arrangement, it is to be understood that the impact rings may be supported in a stationary manner if so desired. However, when these rings are rotated, as shown, the wear upon the inner surfaces thereof will be uniform throughout its circumference and as a result they will last considerably longer than if they are held in a stationary position.

In Figure 3 of the drawing I have illustrated a modified construction for the centrifugal bowl-like rotor, which is here designated by the numeral 50, and also a different form of impact surface, which operates somewhat after the fashion of the impact surface provided in the modified form of mill illustrated in my above identified pending application. As here illustrated, the centrifugal bowl-like element 50 is provided with an axially extending flange 51 at its periphery upon which there is secured a wear-resistant ring 52 of highly refractory material. The wear-resistant ring 52 has a cylindrical flange 53 that telescopes with the flange 51 upon the rotor element 50, and extending through the flanges 51 and 53 there is a plurality of dowels 54 which are driven into the flanges from the inside of the rotor element. The use of dowels 54 for this purpose is desirable, even though not in all cases absolutely necessary, for the reason that the refractory ring 52 is usually cast and is of such a highly refractory character that the dowel holes cannot be drilled and therefore must be formed when the ring is cast. With this arrangement the telescoping arrangement of the flanges 51 and 53 serve to center the refractory ring 52 about the axis of rotation and there is therefore no strain upon the dowels 54.

As here shown, the reduced portion 26 of the housing 18 extends over the centrifugal rotor element 50 in a manner similar to that previously described, but instead of having its impact receiving surface formed by a plurality of wear-resistant rings 28, it has means which will provide for a constantly renewing surface of agglomerate. The means which provides for this constantly renewing impact receiving surface of agglomerate comprises in its simplest form nothing more than an inner lining member 55, which is held in concentric and spaced relation with the cylindrical wall of the reduced portion 26 of the housing 18. The inner lining member 55 is secured in spaced concentric relation within the portion 26 by means of suitable spacing sleeves 56, through which bolts 57 extend. The inner lining member 55 is comprised of two parts, one being designated by the numeral 58 and the other by the numeral 59. The members 58 and 59 are of such a width that except for a space 60 provided therebetween, they will provide a lining throughout the axial length of the reduced portion 26. The space 60 between the portions 58 and 59 of the lining member 55 is so located that it will be substantially and directly in line with the agglomerate which is thrown outwardly under the influence of centrifugal force from the rotor element 50. With this arrangement the sleeves 56 and the bolts 57 are so spaced that they will prevent the free egress of agglomerate which may eventually find its way between the lining member 58 and the outer wall of the portion 26, and back into the larger portion 31 of the rotatable housing 18. The operation of this form

of impact receiving surface may be described as follows:

When the centrifugal rotor element 50 is operating and throwing the agglomerate radially, the agglomerate will accumulate within the compartment provided between the lining members 58 and 59 and the outer wall of the extending portion 26, and as the agglomerate thus accumulates, it will pile up within the space 60 and form a continuously renewing surface of agglomerate against which the centrifugally thrown agglomerate will impact. This impaction between the thrown agglomerate and the piled up agglomerate will thus serve to reduce both the thrown and accumulated agglomerate in the area of the space 60 between the lining members 58 and 59. In my aforementioned copending application the retention of the impact surface of agglomerate is accomplished by rotating the annular portion in which said agglomerate is accumulated at a speed sufficiently high to centrifugally retain a lining of the agglomerate therein, whereas in the present instance I rely entirely upon the rotor 50 throwing the agglomerate at such a rate that the thrown agglomerate will pile up in the space 60 to a depth at least in line with the inner surfaces of the lining members 58 and 59. Under these conditions, it will be readily seen that at the bottom of the spacing 60 there will be no difficulty in retaining a sufficient accumulation of agglomerate. However, since the constantly renewing surface of agglomerate will be rotated as the housing 18 turns upon the rollers 21 and 22 and the agglomerate is discharged from the rotor 50 at a substantially uniform rate in all directions, it will be readily understood that a constantly renewing surface of agglomerate may be retained within the mill in this manner. In order to reinforce the outer wall of the extending portion 26 of the housing 18 and thus avoid damage thereto at starting and during the period of time when the agglomerate impact receiving surface is being built up, I may insert a reenforcing ring 61 in back of the space 60.

The expressions "decanted" and "flootation", as used above in describing the action which takes place when the finely pulverized agglomerate is discharged from the mill, are intended to include the condition where, due to a lack of water, the pulverized agglomerate may be discharged from the mill as a thick muddy mass.

While I have, for the sake of clearness and in order to disclose the invention so that the same can be readily understood, described and illustrated specific devices and arrangements, I desire to have it understood that this invention is not limited to the specific means disclosed, but may be embodied in other ways that will suggest themselves, in view of this broad disclosure, to persons skilled in the art. It is believed that this invention is broadly new and it is desired to claim it as such so that all such changes as come within the scope of the appended claims are to be considered as part of this invention.

Having thus described my invention, what I claim and desire to secure by Letters Patent is—

1. In a centrifugal reducing mill, the combination of an open ended bowl-like element adapted to rotate at high speed and centrifugally throw material to be reduced, hopper means for directing agglomerate to be reduced into said open ended bowl-like element while said element is in rotation, an impact receiving member disposed about the open end of said rotor element, a rotatable drum-like housing adjacent the open end

of said impact receiving member and encircling said hopper for catching the agglomerate discharged from said impact receiving member, said housing having a plurality of buckets disposed about its inner peripheral surface, an annular baffle forming partition adjacent one end of said drum-like housing, means providing a circulation of water through the lower part of said drum-like housing cooperating with said annular baffle to separate the reduced from the unreduced agglomerate and discharging same at the end of said housing, and means for rotating said drum-like housing whereby the buckets disposed therein will return the unreduced agglomerate to said hopper means.

2. In a reducing mill of the character described comprising a centrifugal agglomerate throwing element and an impact receiving member disposed thereabout, the combination of a drum-like rotatable housing adapted to receive the reduced and unreduced agglomerate discharged from said reducing mill, a partition intermediate the ends of said rotatable housing disposed in spaced relation with the cylindrical surface of said housing, buckets within said housing located at one side of said partition and adapted to return the unreduced agglomerate to said reduction mill, means for introducing a circulation of water into the bucket containing part of said housing, and a flaring baffle extending from said partition and cooperating with said circulation of water to separate the reduced agglomerate from the unreduced agglomerate.

3. In a reducing mill of the character described comprising a centrifugal agglomerate throwing element and an impact receiving member disposed thereabout, the combination of a drum-like rotatable housing adapted to receive the reduced and unreduced agglomerate discharged from said reducing mill, a partition intermediate the ends of said rotatable housing and spaced from the cylindrical surface of said housing to permit the discharge of reduced agglomerate, buckets within said housing located at one side of said partition adapted to return the unreduced agglomerate to said reduction mill, means for introducing a circulation of water into said housing, and a truncated conical baffle extending from the spaced outer edge of said partition to prevent the discharge of unreduced agglomerate and cooperating with said circulation of water to separate and discharge the reduced agglomerate from said housing.

4. In a centrifugal reducing mill of the character described, the combination of a rotatable drum having a partition intermediate its ends and spaced from the outer cylindrical wall thereof, to provide a discharge path for reduced agglomerate, an outwardly flaring baffle upon one side of said partition extending outwardly at an angle from the outer edge of said partition, buckets arranged within said drum at the other side of said partition for returning unreduced agglomerate to said mill, and means for introducing a circulation of water through said drum, whereby the finally reduced agglomerate produced by said mill will be carried through the spacing between the wall of the rotatable drum and said partition around said flaring baffle and discharged from said drum.

5. In a centrifugal reducing mill of the character described, the combination of a rotatable drum having a partition intermediate its ends and spaced from the outer cylindrical wall thereof, to provide a discharge path for reduced agglomer-

ate, an outwardly flaring baffle upon one side of said partition extending outwardly at an angle from the outer edge of said partition, buckets arranged within said drum at the other side of said partition for returning unreduced agglomerate to said mill, and means for introducing a circulation of water through said drum, the angle and disposition of said flaring baffle being such that it will permit the passage of reduced agglomerate therearound and redirect the unreduced agglomerate into said buckets as said drum rotates.

6. An impact receiving chamber for a centrifugal mill of the character described, comprising a rotatable cylindrical drum-like member disposed around a centrifugal agglomerate throwing rotor rotating about a horizontal axis, and a cylindrical member disposed concentric with and in spaced relation with the inside wall thereof, said cylindrical member having a relatively narrow annular opening intermediate its ends and in line with the path of the agglomerate thrown from

said centrifugal rotor element, whereby the agglomerate will be thrown therethrough and build up a constantly renewing surface of agglomerate against which the agglomerate thrown by said centrifugal rotor element will impact.

7. An impact receiving chamber for a centrifugal mill of the character described, comprising a rotatable cylindrical drum-like member disposed around a centrifugally operating agglomerate throwing rotor operating about a horizontal axis, and a cylindrical partition disposed concentric with and in spaced relation with the inside wall of said cylindrical drum-like member, said cylindrical partition having a relatively narrow annular opening intermediate its ends and in line with the path of the agglomerate thrown from said centrifugal rotor element, whereby the agglomerate will be thrown thereinto and build up a constantly renewing surface of agglomerate against which the agglomerate thrown by said centrifugal rotor element will impact.

GEORGE FOYE AINSA.
